UNITED STATES PATENT OFFICE.

JOSEPH A. LAWRENCE, OF OLDEN, TEXAS.

SAND TRAP.

Application filed November 27, 1926. Serial No. 151,145.

This invention relates to a sand trap for use in connection with pumps for oil and other wells, and has for its object to provide, in a manner as hereinafter set forth, means to prevent sand from settling down around a pump that is used and is seated in top of a standard working barrel, under such condition preventing the sanding of the pump which often times will not allow of the pump being pulled, resulting in the total loss thereof.

A further object of the invention is to provide, in a manner as hereinafter set forth, means for trapping sand during the operation of a well pump to prevent the sanding of the latter.

Further objects of the invention are to provide, in a manner as hereinafter set forth, a sand trap, which is simple in its construction and arrangement, strong, durable, compact, thoroughly efficient in its use, readily installed, and comparatively inexpensive to set up.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a vertical sectional view illustrating a sand trap, in accordance with this invention, and further illustrating the adaptation thereof in connection with elements of a well pump.

Figure 2 is a section on line 2-2, Figure 1.

Figure 3 is a fragmentary view, in elevation, of the upper end of the guide tube for the pump piston.

Figure 4 is a side elevation of the combined coupling and trap head element.

A sand trap in accordance with this invention, is interposed between, as well as being connected with the tubing sections 1, 2. A pump piston is indicated at 3 and carries at its upper end the foot or standing valve 4, which extends in the tubing section 1.

The trap includes an upper and a lower coupling nipple referred to generally by

the reference characters 5, 6 respectively. The nipple 5 comprises an upper and a lower annular portion 7, 8 respectively, and with the latter of greater diameter than the former. The portion 7 is formed with a peripheral shoulder as at 9. The nipple 5 further includes an intermediate converging portion 10 which leads from the lower portion 8 to the upper portion 7. The nipple 5, at its upper end is peripherally threaded, as at 11, and engaging therewith, as well as seated on the shoulder 7' is the tubing section 1, which has its inner face, at its lower portion threaded, as at 12. The part 8 of the nipple 5 is of greater height than the part 7 thereof and is interiorly threaded as at 14.

The lower coupling nipple 6 is formed from a cylindrical casting, solid with the exception of an axial opening 18'. The nipple consists of a tapered lower portion 15 having depending therefrom a peripherally threaded collar 16. The casting further includes an intermediate portion of two different diameters having that part of larger diameter, which is the lower part of the intermediate portion indicated at 17. The part of smaller diameter is indicated at 18 and peripherally threaded, as at 22. The intermediate portion is formed with a peripheral shoulder 21, which provides a seat for a purpose to be presently referred to. The casting further includes a tapered upper portion 19' having extending upwardly therefrom a collar 19, peripherally threaded, as at 20. The collars 16 and 20 form continuations of the opening 18'.

Mounted on the shoulder 21 and engaging with the threads 22, is a vertically disposed shell 24 which provides the outer wall of a sand receiving chamber 25, to be hereinafter referred to. The inner face of the shell 24, at its upper end is threaded as at 26 and the lower end threaded as at 27. The threads 27 engage with the threads 22 on the portion 17, of the nipple 6.

The shell forms an element of the trap, and the latter further includes the portion 19', collar 19, a pipe member 30, and a combined coupling and trap head element referred to generally by the reference character 31. The element 31 is in the form of an annulus having its periphery threaded, as indicated at 32 and 33.

The threaded peripheral portions 32, 33 are spaced from each other by an annular

rib 34 which projects laterally from the body of the element 31, to provide an upper and a lower shoulder 35, 36 respectively. The rib 34 is interposed between the nipple 5 and shell 24, and the body of the element 31 extends into said nipple 5 and casing 24. When the element 31 is mounted in position, the lower end of the nipple 5 abuts the shoulder 35 and threadedly engages with the threads 32, and the upper end of the shell 24 abuts the shoulder 36 and threadedly engages with the threads 33, and by this arrangement the nipple 5 is coupled with the shell 24 and the element 31 forms the head of the trap.

The element 31 provides an opening 36' for the reception of the reduced upper end 37 of the pipe member 30, the latter provides a guide tube for the pump piston 3 as well as the inner wall of the sand receiving chamber 25. The reduced upper terminal portion 37 of the pipe member 30 provides a shoulder 38 forming a seat for the element 31.

25 A series of radially disposed lengthwise extending wedge shaped channels 40 is formed in the body of the element 31, and said channels 40 provide sand inlet passages for the chamber 25. The top 41 of the element 31 is concave to direct sand towards the inlet passages. The lower end of the pipe member 30 seats on the collar 19, and is further formed with peripheral threads 43 which engage the interior threads of a coupling band 44 coacting with the threads 20 on the collar 19 for securing the pipe member 30 to the coupling nipple 6. The pump piston 3 is adapted to operate through the nipple 5 and element 31.

40 On the operation of the pump, the sand passing the valve 4 will fall into the nipple 5 and from there is conducted by the sand passages into the chamber 40 while the oil will pass up through the tube 1. This operation is had as the sand is heavier than the oil and tends to settle down at all times, therefore, the trap construction as set up reduces the sanding of a pump to a minimum, and furthermore the action of the pump cannot affect the sand which has been collected in the chamber 40.

45 It is thought that the many advantages of a sand trap, for the purpose set forth and in accordance with this invention, can be readily understood, and although the preferred embodiment of the invention is as illustrated and described, yet it is to be under-

stood that changes in the details of construction can be had which will fall within the scope of the invention as claimed.

60

What I claim is:—

1. A sand trap for well pumps comprising an upper and a lower nipple and adapted to have a pump piston extend therethrough, a vertical shell connected to said lower nipple, an annular member extending into and secured to said shell and upper nipple and formed with a series of openings, a pipe supporting said member and connected to said lower nipple, adapted to surround the pump piston and forming in connection with said member, said lower nipple and said shell, a sand receiving compartment, the openings in said member forming inlets for said compartment.

75

2. A sand trap for well pumps comprising an upper and a lower nipple and adapted to have a pump piston extend therethrough, a shell connected to said lower nipple, an annular member extending into and secured to said shell and said upper nipple and having its body portion formed with a series of openings, a pipe supporting said member and connected to said lower nipple, adapted to surround the pump piston and forming in connection with said member, said lower nipple and said shell, a sand receiving compartment, the openings in said annular member forming inlets for said compartment, said annular member having a concave top.

85

3. A sand trap for well pumps comprising a lower nipple, an upper nipple provided at its top with an inwardly extending flange, said nipples adapted to be connected to tubing sections, and have a pump piston extend therethrough, a shell connected at its lower end to said lower nipple, an annular member secured to the lower end of said upper nipple and to the upper end of said shell and having its body formed with a series of vertical openings, a pipe having its upper end extending into and supporting said member and further connected with said flange and through which extends the pump piston, said member, pipe, flange and shell forming a sand receiving compartment, the openings in said member providing inlets for said compartment, said member having a concave top.

95

100 In testimony whereof, I affix my signature hereto.

JOSEPH A. LAWRENCE.
